UNITED STATES PATENT OFFICE.

ROBERT A. NUGENT, OF SOMERVILLE, MASSACHUSETTS.

METHOD OF MAKING OPEN CORES.

1,310,768.

Specification of Letters Patent. Patented July 22, 1919.

Application filed May 6, 1919. Serial No. 295,067.

To all whom it may concern:

Be it known that I, ROBERT A. NUGENT, a citizen of the United States, residing at Somerville, in the county of Middlesex and 5 State of Massachusetts, have invented new and useful Improvements in Methods of Making Open Cores, of which the following is a specification.

In the manufacture of many metal castings, *e. g.* for globe or gate valves, it is necessary to employ open cores, so that the casting when finished will have an internal web or other component. The preparation of such open cores has heretofore been a 15 tedious and expensive operation, requiring delicate manipulation and a high degree of skill on the part of the core maker. I have devised a process for the manufacture of such cores, which requires no greater skill 20 or accuracy of workmanship than the manufacture of solid cores.

On the accompanying drawing,—

Figure 1 illustrates the finished core.

Fig. 2 represents the core before it is 25 baked with the fusible section in place.

Fig. 3 shows one of the molds for casting the fusible sections.

Fig. 4 represents one member of the core box.

30 Fig. 5 represents one of the fusible sections.

Fig. 6 illustrates a section of a finished globe valve body produced (except for the threading) by the use of the core shown in 35 Fig. 1.

As has been stated, it has heretofore been a delicate and tedious operation to produce an open core such as shown for example in Fig. 1. In this figure, the core is provided 40 with the two opposite cylindrical end members *a a* and the lateral cylindrical member *b*. These extend from a convex body which is roughly elliptical in longitudinal section and circular in cross section, but which in 45 fact consists of the two similar portions *c c* connected by the integral central pillar *d*. Such a core is utilized in casting a valve body 10 as shown in Fig. 6, in which the web 11 divides the body into two chambers 12, 50 13, with the port 14 opening from one into the other. The space between the portions *c c* of the core permits the metal to flow between them for the formation of the web 11, whereas the presence of the connecting 55 pillar insures the formation of the port or opening 14. The web, as shown, has a longi-

tudinal portion in the axis of the body extending from one side wall to the other with one end upturned as at 112 and the other end downturned as at 113 and merging in the wall of the body so that one end opening 15 communicates with the chamber 13 and the other end opening 16 communicates with the opening 12. This is standard construction, and the finished core does not 60 differ from those employed in producing it, so that it will be understood that they are selected only as illustrations in making clear what is meant by an "open core" and in describing the results which may be secured 65 by the process which I shall now describe in producing an open core.

My process consists broadly in building or forming the core with a section of fusible material which is incorporated in the core 75 when it is initially formed and molded, but which, when the core is baked, melts and flows from the core leaving the latter with a free space or opening, such for example as may be necessary in casting an internal 80 web 11 as described.

Assuming that it is desired to produce a finished core as in Fig. 1, I proceed as follows: By means of suitable molds (to be described) I produce a fusible section or 85 member *e*, as shown in Fig. 5, which has the shape and dimensions of the web 11, 112, 113, except that at what may be called its ends it had the lugs *f f*. Such member has at its center an aperture *g* which is formed 90 by the core material (*i. e.* sand or the like with the usual adhesive) to insure the formation of the post or pillar *d*.

In forming the core, I employ a core box 95 consisting of two sections 17, one of which is shown in Fig. 4, and which are doweled together as usual. Said sections are jointly formed with an internal cavity or chamber 18 of the shape of the finished core, except that at 19, 19, it is provided with notches 100 or recesses to receive the lugs *f* of the fusible member *e*. The sections of the core box are first separated and the member is placed as shown in Fig. 4 with the lugs located in the recesses 19, said lugs and recesses being 105 angular and complementary to hold the member against dislocation. On closing the core box, the operative fills the box completely with the mixture of core-making material, so that it will be packed and compressed 110 solidly therein and fill the opening *g* of the member *e*. Then the core box is opened and

the core removed, the fusible member forming a part of the core, as shown in Fig. 2. The core is now placed in the oven for baking, being placed upright and standing on the flat end of the member *b*. A pan or tray is used for receiving a number of the cores. The oven is heated to the temperature required thoroughly to bake the cores, this temperature being sufficiently high to 5 melt the fusible members *e*, the molten material flowing from the core and being caught by the pan or tray. When the cores have been thoroughly baked, they present the appearance of that shown in Fig. 1. The 10 molten material caught by the trays may be re-used in forming the sections *e*. As shown, the exposed surfaces of the section (except the ears or lugs *f*) are flush with the surfaces of the core before it is backed, but 15 this depends upon the conformation of the ultimate casting.

In Fig. 3, I have indicated a sectional mold for casting the fusible members *e*. It consists of two mold box sections, of which 20 one is shown at 20, having the recesses 21 and the mouth 22 to receive the molten material. 23 and 24 are removable elements (corresponding to the portions *c c* of the core) and pin 25 which corresponds to the 25 pillar *d*. These parts may be formed of brass or other suitable material. After the molten material has been poured in the mold and has cooled and set, the mold is opened, the elements 23, 24 and 25, with the casting 30 between them are removed, the pin 25 withdrawn, and the elements 23 and 24 separated 35

leaving the casting or member as shown in Fig. 5.

In forming the member *e*, I prefer to use Rose's metal or other metal alloy which has 40 a low fusing point, but may use, if desired, a wax or other composition which will be initially hard and unyielding and yet melt at a temperature at which the cores are baked. 45

What I claim is:—

1. A process of making open cores which consists in forming a fusible member in the shape of the opening in the completed core, then forming the core of the usual material 50 about said member, so that said member is embedded in such initially formed core, then baking said core and fusing said member so that it will flow from the core, leaving the latter in its finished open condition. 55

2. A process of making open cores which consists in forming a fusible member in the shape of the opening in the completed core and with an aperture therethrough, placing such member in a core box and packing the 60 usual core-making material around such member and within the aperture therein, permitting the thus initially formed core with said member therein to set, then baking such core at a temperature at which said 65 member fuses, thereby melting said member and permitting it to flow from the finished core.

In testimony whereof I have affixed my signature.

ROBERT A NUGENT.
